UNITED STATES PATENT OFFICE.

FRANCIS M. FLOYD, OF ELKVILLE, ILLINOIS.

ROTARY FLUID-PRESSURE MOTOR.

1,166,044.

Specification of Letters Patent. Patented Dec. 28, 1915.

Application filed January 27, 1915. Serial No. 4,735.

To all whom it may concern:

Be it known that I, FRANCIS M. FLOYD, a citizen of the United States, residing at Elkville, in the county of Jackson and State of Illinois, have invented certain new and useful Improvements in Rotary Fluid-Pressure Motors, of which the following is a specification.

This invention relates to rotary fluid pressure motors and more particularly to that type in which the gaseous mixture is exploded in a combustion chamber and the resulting products of combustion are subsequently admitted under pressure to the piston chamber, and it is one aim of the invention to simplify the construction of such motors and to render the same more efficient.

One object of the invention is to so arrange the explosion chamber that it will serve also as a valve for controlling the admission of the explosive charge to it and for controlling the passage of the products of combustion from it to the piston chamber.

The invention also contemplates so constructing and arranging the explosion chamber that it may serve as a timer, thereby obviating the necessity of employing a separate and distinct device for this purpose.

Another aim of the invention is to provide between the inlet to the piston chamber and the exhaust therefrom a novel means for closing the said chamber between these two points during a predetermined travel of the piston, so that the piston will receive the full force of the exploded charge practically up to the moment of exhaust, and incidentally the invention aims to provide novel means for moving the gate into and out of position to close the said piston chamber.

In the accompanying drawings: Figure 1 is a vertical front to rear sectional view through one of the motors embodying the present invention. Fig. 2 is a view partly in elevation and partly in transverse section illustrating a pair of the motors. Fig. 3 is a view similar to Fig. 2, but viewing the opposite side of the structure. Fig. 4 is a transverse sectional view. Fig. 5 is a view in side elevation of the cam disk which constitutes an element of the means for actuating the explosion chamber and the gate.

Corresponding and like parts are referred to in the following description and indicated in all the views of the accompanying drawings by the same reference characters.

In the drawings, two of the motors embodying the present invention are illustrated as arranged in connected relation, but it will be understood that one or more than two of the motors may be so connected and inasmuch as the motors are of counterpart construction a description of one will suffice for both.

Each of the motors includes a casing which is mounted in any suitable manner upon a base 1 and this casing is formed in two lateral halves or sections provided with flanges 2 permitting of the sections being connected together by bolts 3. For convenience in describing the construction of the casing, the same will hereinafter be referred to as though cast integral throughout. The casing includes an annular piston chamber 4 and spaced sides 5 concentric to the said chamber and provided axially with laterally projecting collars or bearings 6 for the shaft of the motor, the said shaft being indicated at 7. The inner ends of the collars 6 are inferiorly increased in diameter as indicated at 8, and receive the ends of the hub 9 of the rotor, the rotor consisting in part of a disk 10 integral with the said hub and rotatably fitting between the sides 5 of the casing. The hub 9 of the rotor is of course keyed or secured in any other suitable manner to the shaft 7. In order that there may be no leakage of the motive fluid, the inner faces of the sides 5 of the casing and the faces of the rotor disk 10 are formed with registering annular grooves 11 receiving packing rings 12. The disk 10 of the rotor carries a piston including a head 13 which is preferably cast integral with the periphery of the disk and at one end is of a diameter to snugly fit within the piston chamber 4. This piston also includes a head 14 and packing rings 15 and the rings 15 are disposed between the heads 13 and 14 and a bolt 16 is secured through the head 14 and through the packing rings and into the head 13. The wall of the piston chamber is provided with an inlet port 17 and the head 14 of the piston has an inclined or oblique face 18 which is presented at an angle toward the said port 17 and it is against this face of the piston that the exploded charge is directed.

The casing for the motor is provided at its top with a hollow spherical secondary casing including an outer wall 19 and an inner wall 20, the space between the walls forming a water jacket, indicated at 21, and this

jacket is provided with an inlet 22 and an outlet 23 and is to be supplied with water in any suitable manner. The interior of the secondary casing, considered as a whole, is smoothly ground, and receives for oscillatory movement a hollow spherical explosion chamber 24. The walls 19 and 20 of the secondary casing are integrally connected at diametrically opposite points to form bearings 25 and 26. The explosion chamber 24 is provided at one side with a solid trunnion 27 and at a diametrically opposite point with a hollow trunnion 28 which is placed in communication with the interior of the said chamber 24 by a relatively small passage 29. The trunnions 27 and 28 are rotatably fitted respectively in the bearings 25 and 26. Into the end of the trunnion 28 there is fitted a spark plug 30 which has secured to its outer end a timer disk 31, the periphery of which is of insulating material, as indicated at 32, except at the point of contact which is indicated at 33. A bracket 34 is secured upon the wall 19 and carries a brush 35 which has its end resting in engagement with the periphery of the timer disk. The bracket 34 is of course insulated from the wall 19 and a conductor wire 36 is connected to the arm 28 for the purpose of conducting an electric current through the arm to the brush 35 and through this brush and the timer disk. When the contact point 33 is in contact with the brush, and to one of the terminals of the spark plug, the current being grounded across the gap between the two terminals of the spark plug in the ordinary manner. The wall of the explosion chamber is provided with a port 37 which is designed to be brought into registration with the port 17 in the wall of the piston chamber under conditions which will be presently explained, and the said port 37 is also designed to be brought into registration with a port 38 opening through the walls of the secondary casing. A needle valve casing 39 is secured to the secondary casing and has its outlet 40 in communication with the port 38 and this valve casing is provided with an inlet 41 for the liquid fuel and with an inlet 42 for air under pressure. The needle valve proper is indicated by the numeral 43 and by reference to Fig. 1 of the drawings it will be apparent that it may be adjusted so as to control the supply of the air under pressure to the valve casing. It will now be understood that the air under pressure being admitted to the valve casing, will flow past the needle valve and will atomize the liquid fuel entering through the passage 41, the gaseous mixture thus formed passing through the ports 40 and 38 and into the explosion chamber when the port 37 is in communication with the port 38.

In order that the explosion chamber may be oscillated upon its trunnions so as to

bring the port 37 successively into registration with the ports 38 and 17, a gear 44 is fixed upon the projecting end of the trunnion 27 and meshes with a segmental gear 45 located at the outer end of a rock arm 46. The arm 46 is mounted between its ends for oscillatory movement, as indicated at 47, and at its end opposite its end which carries the segmental gear, is provided with a roller 48.

The numeral 49 indicates a cam disk 75 which is fixed upon the shaft 7, in the present instance between the two motors, and this disk is provided in each face with a cam groove 50, the contour of which is clearly shown in Fig. 4 of the drawings. 80 This groove is continuous and for a portion of its length is concentric to but relatively remote from the shaft 7, as indicated at 51, the remaining portion of the groove, indicated at 52, being also concentric to the shaft 85 but located relatively close thereto. It will now be understood that upon rotation of the disk 49 the arm 46 will be oscillated as the walls of the portions 51 and 52 of the cam groove 50 ride over the roller 48, and due to the gear connection between the arm and the trunnion 27 of the explosion chamber this chamber will be oscillated in the manner heretofore described. When the roller 48 is in the portion 52 of the cam groove 50 the chamber 24 will be in position with its port 37 in communication with the port 38 and at this time the explosive charge will be permitted to rush into the said explosion chamber. Upon the continued rotation of the shaft 7 and the cam disk 49 and as the roller 48 enters the portion 51 of the cam groove, the explosion chamber will be oscillated in a direction to move the port 37 past and out of communication with the port 38. As the port 37 passes the port 38 the contact point 33 of the timer disk will come into contact with the brush 35 and a portion of the mixture, having entered the hollow trunnion through the passage 29, the mixture will be exploded. Upon further rotation of the disk 49 the explosion chamber will continue to move in the direction stated until the port 37 registers with the port 17, whereupon the products of combustion under high pressure will be allowed to rush from the explosion chamber into the piston chamber and against the inclined face of the piston head. This operation is of course repeated during the revolution of the shaft 7, and the cam disk 110 115 120 carried thereby.

The wall of the piston chamber is provided with an exhaust port 53 and, as before stated, a gate is provided movable into and out of position to close the piston chamber between this port and the inlet port 17. This gate is indicated by the numeral 54 and is in the nature of a plate mounted at its lateral edges in the grooves 55 formed in the spaced portions of a guide 56 integral 130

with the side walls of the piston chamber. By reference to Fig. 5 of the drawings it will be observed that the grooves 55 are relatively deep and that they open into the piston chamber and for this reason the gate is relatively wide or, in other words, of greater width than the interior of the piston chamber and may consequently completely close the said chamber, when in the position 10 shown in Fig. 1 of the drawings. A bracket 57 is mounted upon the wall of the casing and mounted for oscillatory movement upon this bracket is a segmental gear including toothed portions 58 and 59. The gear 58 meshes with a rack 60 upon the under side of the gate 54 and the gear 59 meshes with a segmental gear 61 at one end of a rock arm 62, mounted for oscillatory movement, as at 63, upon the wall of the casing. This arm 20 62 includes an extension 64 carrying a roller 65 which works in a cam groove 66 formed in the side of the cam disk 49 and surrounding or located exterior of the groove 50. The groove 66 for a portion of its length is 25 concentric to the shaft 7 and located relatively remote therefrom and this portion is indicated at 67. The groove also includes a portion 68 which is also concentric to the shaft but located nearer thereto than the portion 67. By reference to Fig. 1 it will be observed that when the roller 65 is in the portion 67 of the groove 66 the gate 54 will be in position to close the piston chamber between the inlet and exhaust ports thereof, and it will further be understood that as the cam disk is rotated and the walls of the portion 68 of the groove 66 travel past the roller 65 the arms 62 and 64 will be oscillated and, by reason of the connection between the arm 62 and the segmental gear 59 and the connection between the gear 58 and the gear 60, the gate 54 will be slid in an outward direction so as to allow the piston to pass, after which the gate will be automatically returned to the position shown in Fig. 1.

Mounted upon the motor casing is a compressed air storage tank 69 having an inlet connected by a pipe 70 with the inlet 42 to 50 the needle valve casing. In order that the air may be pumped into the tank 69 while the motor is in operation, air pumps are provided and each of these pumps includes a cylinder 70 mounted upon a suitable support 71 which, in the present instance, extends between the motor casings and an air supply pipe 72 leads from the pump cylinder to the tank 69. Each cylinder 70 is provided in its head with a check valve 73 and 55 mounted to reciprocate in each cylinder is a piston, the head of which is indicated by the numeral 74 and is provided with a spring pressed check valve 75. A pitman 76 is connected to the piston head and to the strap 77 60 of an eccentric 78 fixed upon a shaft 79

mounted in suitable bearings 80 upon the motor casings. The shaft 79 is driven from the shaft 7 through the medium of the gearing shown in Fig. 3 and indicated at 81.

Having thus described the invention, what is claimed as new is:

1. In a motor of the class described, a piston chamber having an inlet port, a casing in communication with the port, a piston working in the chamber, the casing having a fuel inlet port, a shaft driven through the travel of the piston, an explosion chamber mounted for oscillatory movement within the casing and having trunnions projecting from the wall of the casing at diametrically opposite points, one of said trunnions being hollow and in communication with the interior of the said explosion chamber, a spark device mounted within the said trunnion and arranged for oscillation therewith, a timer oscillated through the medium of the said spark device, a contact for the timer, a cam member mounted upon the said shaft, and a movable member operatively connected with the other one of the said trunnions and actuated through the medium of the cam member for oscillating the explosion chamber. 80

2. In a motor of the class described, a piston chamber having an inlet port, a casing in communication with the port, a piston working in the chamber, the casing having a fuel inlet port, a shaft driven through the travel of the piston, an explosion chamber mounted for oscillatory movement within the casing and having trunnions projecting through the wall of the casing at diametrically opposite points, one of said trunnions being hollow and in communication with the interior of the said explosion chamber, a spark device mounted within the said trunnions and arranged for oscillation therewith, a timer oscillated through the medium of the said timing device, a contact for the timer, a cam member mounted upon the said shaft, a gear mounted upon the other one of the said trunnions, and a rock arm having operative connection with the gear and with the said cam. 100

3. In a motor of the class described, a piston chamber having an inlet port, a casing in communication with the port, a piston working in the chamber, the casing having a fuel inlet port, a shaft driven through the travel of the piston, an explosion chamber mounted for oscillatory movement within the casing and having trunnions projecting from the wall of the casing at diametrically opposite points, one of said trunnions being hollow and in communication with the interior of the said explosion chamber, a spark device mounted within the said trunnions and arranged for oscillation therewith, a timer oscillated through the medium of the said timing device, a contact for the 115
120
125
130

timer, a cam member mounted upon the said shaft, a gate slidable into and out of position to close the piston chamber between the exhaust and inlet thereof, and operative connection between the gate and said cam member for actuating the gate.

4. In a motor of the class described, a piston chamber having an inlet port, a casing in communication with the port, a piston working in the chamber, the casing having a fuel inlet port, a shaft driven through the travel of the piston, an explosion chamber mounted for oscillatory movement within the casing and having trunnions projecting through the wall of the casing at diametrically opposite points, one of said trunnions being hollow and in communication with the interior of said explosion chamber, a spark device mounted within the said 20 trunnions and arranged for oscillation there-

with, a timer oscillated through the medium of the said spark device, a contact for the timer, a cam member mounted upon the said shaft, a gear mounted upon the other one of the said trunnions, and a rock arm having operative connection with the gear and with the said cam, a gate slidable into and out of position to close the piston chamber between the exhaust and inlet thereof, a rack upon the gate exteriorly of the piston 25 chamber, and an oscillatory gear member meshing with the rack and actuated through the rotation of the cam member.

In testimony whereof I affix my signature in presence of two witnesses.

FARNCIS M. FLOYD.
